UNITED STATES PATENT OFFICE.

HARRY WARD LEONARD, OF BRONXVILLE, NEW YORK,

AUTOMATIC THERMO-ELECTRIC CONTROL.

No. 915,974.

Specification of Letters Patent. Patented March 23, 1909.

Application filed January 5, 1908. Serial No. 284,691.

To all whom it may concern:

Be it known that I, HARRY WARD LEONARD, a citizen of United States, residing at Bronxville, in the county of Westchester and 5 State of New York, have invented certain new and useful Improvements in Automatic Thermo-Electric Control, of which the following is a full, clear, and exact specification.

My invention relates to the production and 10 to the control of heat, and its principal object is to secure a desired control automatically.

In most forms of my invention the effects of 15 heat are utilized to affect an electric circuit in which an electro-responsive device is employed, and which responds to automatically control, as desired, whatever is to be controlled.

An important application of my invention 20 is to a soldering iron. In using a soldering iron, the rate at which heat is emitted by it should be widely variable to secure the best results. When the soldering iron is not being used, its temperature should not increase 25 abnormally. On the other hand, when the soldering iron is being used rapidly in soldering, for example, the conductors of an armature to the commutator bars in a dynamo electric machine of considerable size, the soldering iron should not become cool. In 30 order to maintain a soldering iron at a fairly uniform temperature under such widely varying conditions of heat withdrawal, it is desirable that the production of heat energy 35 in the soldering iron should be automatically proportioned to the rate at which heat is to be emitted by the iron to suit the requirements of practice. By means of my invention, this result is secured, and is particularly 40 applicable to electrically heated soldering irons.

My invention is also very advantageous 45 for use in connection with electrically heated flat irons. In such electric flat irons as have been before employed, they become too hot when not in use, and too cool when they are employed to iron damp goods at the highest rates at which a workman can work. The 50 large amount of energy required to convert the water contained in the goods into steam, tends to cool the iron and this greatly reduces the commercial value of an electrically heated flat iron as compared with the value it would have if its temperature could be maintained 55 approximately constant, regardless of the character of the goods ironed, their condition

as regards dryness, the rate at which the iron is moved over the goods and the pressure applied, and regardless of whether the iron is in use or idle.

Many attempts have been made to accomplish to some degree these desirable objects, but so far as I am aware, no one has heretofore successfully and commercially obtained these results which my invention accomplishes.

My invention is susceptible of various modifications as will be apparent from the following description and accompanying drawings, and the scope of my invention is indicated by the appended claims.

Figure 1 is a diagram of apparatus and connections showing an application of my invention; Figs. 2 to 13 are similar diagrams of modifications; Figs. 14 and 15 are sectional views showing the arrangement of the resistance in one form of soldering iron; Fig. 16 is a longitudinal sectional view of another form of soldering iron; Fig. 17 is a section on the line 17-17 of Fig. 16; and Fig. 18 is a diagram indicating a desirable arrangement of resistances or coils in a flat-iron.

In accordance with my invention as shown in the accompanying drawings, I place in good heat conductive relationship to the heat generating device, such as the resistance, a device which responds to a change in the temperature of the heat generating device, and this responsive device is arranged to affect the current in a circuit which contains electro-responsive means, which latter accomplishes a change in the heat production. The heat or temperature is thereby automatically regulated.

Referring to Fig. 1 a source of energy 95 is indicated at 1 which supplies current to the supply mains 2, 2'. At 3 is indicated a heating resistance connected across the supply wires through a resistance 4. The latter resistance may sometimes be variable for the purpose of adjustment, as explained below, and the resistance 4 is therefore shown as divided into a series of steps and as having an adjustable arm 5 to vary the amount of resistance in circuit. Adjacent to the arm 5 is a scale 6 which may be graduated to enable the operator to readily secure whatever adjustment he desires. In good thermo-relation to the device heated or to the resistance 3 is placed a wire 7, having a considerable temperature coefficient, such as a wire of nickel or iron. The wire 7 is connected

across the supply mains 2, 2' through an electromagnetic winding 8. The winding 8 is provided with an iron core and a pivoted armature 9. The armature 9 is connected in circuit electrically as shown so that when it is attracted by its magnet it will engage the contact 10 and short circuit the resistance 4. A stop 11 is provided for the armature to limit its downward movement, and this together with the contact 10 is preferably made adjustable, as by means of a screw as indicated. A graduated scale 12 is preferably arranged in some cases adjacent to the armature for the purpose of indicating to the operator the adjustment secured.

In operation, assuming that the desired adjustment is secured and the armature 9 attracted, the resistance 3 will give out heat until the temperature is raised to a predetermined amount, and as the temperature is increased the resistance of the wire 7 very appreciably increases and gradually diminishes the current flowing through it and the winding 8, until at the maximum limit desired, the current becomes so weak through the winding 8, that it releases its armature 9 which then falls to the position shown in Fig. 1. This will insert resistance 4 in series with the heating resistance wire 3, and thereby cut down the current passing through the wire 3 so that its heating effect is diminished. When the heat of the parts is reduced to a certain limit, the resistance of the wire 7 decreases so much that the increased current which then flows is sufficient to cause the magnet of coil 8 to attract its armature 9. The engagement of this armature with the contact 10 short circuits the resistance 4, which causes an increased current to flow through the heater 3. The temperature will consequently again rise to such an amount that the current through the wire 7 and coil 8 is so reduced that the armature 9 is no longer retained by its magnet and again falls. This will reduce the heating effect of the wire 3 by inserting resistance 4 in series with it across the line, as above explained. These actions are continued and thus maintain a practically constant temperature of the device heated. It will be observed that with this arrangement, the temperature of the heated device is automatically controlled, regardless of the rate at which the heat is taken away from the soldering iron or other device to be heated. The heat generating wire can therefore be worked at the maximum temperature commercially allowable with good results, and at the same time will be protected from exceeding such temperature.

In many instances, it will be desirable to have a certain stable condition automatically maintained, and yet have means controllable by the operator to vary the conditions as desired. For example, it may be desirable to

use one constant temperature on a flat iron when working on one kind of goods, and a different constant temperature when working on another kind of goods. Adjustment will also be desirable in connection with other applications of my invention. This may be accomplished by varying the air-gap on the magnet. For this purpose, I have indicated the stop 11 as adjustable, as well as the contact 10, and it will be desirable to place a scale, such as 12, adjacent to the armature of the magnet, which scale may be calibrated in degrees for convenience of the operator. The operator can thus adjust the armature to a position corresponding with a certain desired temperature, which temperature will be automatically maintained. Another adjustment for this purpose will be to provide the armature 9 with an adjustable weight, such as 13. Likewise, other forms of adjustment may be provided. The resistance 4 is preferably adjustable so as to vary the minimum current which will pass through the heater 3 at the will of the operator, and a calibrated scale 6 may be provided to indicate the minimum amount of heating which will be secured when the resistance 4, or parts thereof, are in circuit. In the same way it will be desirable to provide an adjustable resistance, such as 14, in series with the heater 3, and outside of the shunted resistance so that by adjustment of this resistance 14 the maximum current flow through the heater may be varied. A suitable scale 15 may be provided and so calibrated as to indicate the maximum flow of current, and the maximum amount of energy to be dissipated.

It is desirable to make the air gap of the controlling magnet sufficiently large or the magnetic circuit be so designated, that the magnetic pull upon the armature with the same amperes is nearly the same when the armature is at one limit of its travel as when at the other limit of its travel, so that a slight change in the current strength will cause the armature to be attracted or released and thus make the apparatus quite sensitive.

In most instances, it is very advantageous to have the automatic controlling device outside of the tool, or other object heated, as it is then not subjected to any considerable heat and can be readily inspected, adjusted, repaired etc., without interference with the device controlled. Also this arrangement is desirable, as the controlling device does not occupy space on the tool or other device controlled, and does not unfavorably affect its weight and size, and the tool may be made more rugged and simple. In some special cases however, it may be desirable to have the automatic controlling device located in immediate proximity to the source of heat, and perhaps contained in the same apparatus. It is obvious that instead of using

gravity to oppose the attraction of the controlling magnet upon its armature, as in Fig. 1, a spring or other pressure may be substituted, and if the controlling means is located 5 in the tool itself, a spring would probably be preferable.

By means of my invention, the current in the heating resistance may be varied extremely, and thus make a heated tool respond quickly and efficiently to the changes 10 in the rate at which heat energy is drawn from the tool, and the heating resistance may be subjected for short periods to currents which, were they not automatically reduced 15 by the controller, would soon cause the resistance to be burned out. Thus, while obtaining high temperatures, I avoid subjecting the resistance to destructively high temperatures and thus greatly prolong its life. 20 With the excessively high temperatures, which former apparatus acquired when standing idle, the working surface of the tool was likely to be injured and there was also likelihood of bad effects upon the work when the 25 tools were put into use. For example, a soldering iron would have its surface oxidized so that the solder would not flow well on its surface, and a flat iron would be likely to scorch the goods to which it was applied 30 when overheated, due to standing idle.

One of the greatest advantages which my invention accomplishes, is that a workman's output can be very greatly increased, since the temperature of the tool will be automatically 35 maintained substantially constant no matter how rapidly the operator may work, and no matter what the character of the goods is which are worked upon. As the output and quality of work done by the operator is the 40 most important factor in such cases, a great economy results even though the cost of electric energy is comparatively high, and even though first cost is greater.

Instead of using a wire 7 of nickel or some 45 similar resistance, it may sometimes be desirable to use a material having a negative coefficient instead of a positive temperature coefficient. In such a case the arrangement might be that shown in Fig. 2, in which the 50 wire 7 is replaced by a material 7' of negative temperature coefficient, and in which the parts 10 and 11 of Fig. 1 are transposed. Thus, when the temperature of the heater or tool rises to the maximum amount, the current 55 in the circuit containing the coil 8 will be increased on account of the decrease in resistance, and the armature 9 will be attracted causing the resistance 4 to be inserted in series with the heat producer 3, 60 and so reduce the effective heating. Also, when the temperature becomes lower, the resistance 7' increases, which reduces the current through coil 8, causing the release of armature 9 and so short circuits the resistance 4 to cause the heating effect of 3 to

be increased. In Fig. 2, I have indicated an additional means for adjusting the action of the automatic controller. This is the insertion of a variable resistance 16 in the circuit of coil 8, and this variable resistance may 70 be provided with a calibrated scale 17 which will indicate to the operator the effect that will be produced. As this variable resistance will determine the current that will flow in the coil 8, its adjustment will determine within certain limits the temperature 75 of the part 7' that will cause the attraction or release of the armature 9 by its magnet.

It may sometimes be desirable to employ a relay device in connection with the controlling apparatus, as when the watts controlled are too large to be readily carried without the relay device, or where increased sensitivity is desired. An arrangement of this kind is illustrated in Fig. 3. In this case 80 the circuit controlled by the movement of armature 9, is that of a solenoid switch 18. When the solenoid switch is closed by the movement of armature 9 to the contact 10, the resistance 4 in series with the heat 85 producer 3 is short circuited, causing the amount of heat yielded by 3 to be increased. As soon as the temperature is raised as before described, the increased resistance of the wire 7 will cause the armature 9 to be released, which will break the circuit of the 90 exciting coil of switch 18, which latter will then open. This will insert the resistance 4 in series with the heat producer 3, and reduce the heating effect as already explained. In 95 the present figure, I have shown the adjustable resistance 16 as shunting the coil 8, instead of being in series with it as in Fig. 2. Variation of this shunt resistance around 100 coil 8 will, of course, vary the current that will flow in the latter and likewise afford means for adjustment of the apparatus so that it will operate to maintain a desired condition of temperature.

My invention may be useful in some cases 110 to the control of heat which is not derived from a source of electricity. For example, I may employ the temperature of a furnace, or of a liquid, solid, or gas to act upon the heat responsive controlling resistance, and thereby control the gas flame which may be the source of heat, or I may control dampers, fans or other means which will control the production of heat as desired at its place of application. Similarly, I may control a 115 refrigerating instead of a heating apparatus, whereby the temperature at some desired location will be automatically maintained within certain limits. Fig. 4 illustrates an instance of application of my invention to 120 the control of this character. This indicates a material 19, which is heated by a gas jet 20, and the supply of gas is controlled by a valve 21. The valve is controlled by a core 22, the coil 23 of which is connected in series with 125

the heat responsive resistance 7. The movement of the valve 21 is limited by the adjustable stops 24, 24. When the temperature of the body 19 has reached a predetermined amount, the current through the resistance 7 and coil 23 will be so reduced that the core 22 will fall and turn the valve to decrease the supply of gas. On the other hand, when the temperature becomes lower, the current through the coil 23 and resistance 7 is increased and the core 22 is raised, and the valve 21 will then be opened to supply a greater amount of gas and heat to the material 19.

15 My invention may sometimes be employed to give an audible, visual, or other form of signal when the temperature exceeds a certain predetermined limit. This is shown in Fig. 5, in which, when the temperature and the resistance of 7 rises to a predetermined amount, the armature 9 will be released and close a circuit through an electric bell 25, or an electrical lamp 26, or both. A decrease of temperature and consequent increase of current through the coil 8, will cause the armature 9 to be attracted which will break the circuit of the signal or signals, and show that the temperature is below the maximum limit.

30 It may sometimes be desirable to employ two or more controlling magnets, each controlling a set of resistance so as to secure greater refinement of automatic control of the heat generated, and to secure other advantages which may arise from the employment of several steps as compared with one step. An arrangement in which two steps of resistance are used with two controlling magnets is shown in Fig. 6. In addition to the parts shown in Fig. 1, a second set of controlling means is shown, having corresponding numerals to designate the same parts, except that the numerals of the additional set are primed. The resistances 16, 45 16' form variable resistance shunts around the coils 8, 8' so that each may be adjusted to cause their armatures to be attracted and released upon the occurrence of certain definite currents through the responsive resistance 7. The coil 8 may be adjusted and

50 designed to attract the armature 9 upon the occurrence of a greater current through the resistance 7, than that upon which the coil 8' will attract its armature 9'. In such a case, if the temperature of the device to be heated drops below a certain amount, the armature 9' will first be attracted and cut out the resistance 4' to increase the heating effect of the heat producer 3. If this proves 55 to be insufficient to raise the temperature, and a further drop in temperature occurs, the armature 9 will then be attracted and short circuit the resistance 4, which will cause a further increase in the heat production.

60 Likewise, if the temperature becomes equal

to a certain amount, so that the resistance of 7 is increased to a certain degree, the armature 9 will first be released, and if this does not reduce the heating sufficiently by the insertion of resistance 4, and if the temperature is further increased, the armature 9' will next be released and the heating effect will be further reduced by the insertion of resistance 4'. Similarly, if desired, a greater number of controlling devices may be used.

70 Instead of using a responsive material of variable resistance upon change of temperature, and thereby control the current in an electro-responsive device, a thermostat or other device may be used, in which a change 75 in temperature causes a mechanical movement. When such movement occurs, an electrical contact will be made or broken to control the current leading to an electro-responsive device which will control the insertion or cutting out of resistance to affect the heat production. Fig. 7 shows an arrangement of this character, a thermostat 27 being placed in good heat conductive relation to the heater 3. When the heating has raised 80 the temperature of the device to a certain amount, the movement of the thermostat will be such that it moves away from a pair of contacts 28, opening the circuit of coil 29 of an electro-magnetic switch 30. The switch 85 30 is then opened and the resistance 4 inserted in series with the heat producer 3 to reduce the heating effect. When the device has cooled to a certain temperature, the thermostat will move to engage the contact 28, 90 closing the circuit through coil 29, and thereby closing the switch 30. This cuts the resistance 4 out of circuit and increases the heating effect as already explained. My invention may also be applied to the protection 95 of armatures of dynamo electric machines, or other devices which may become unduly heated, so that when the temperature exceeds a predetermined maximum, the heat responsive device associated therewith will 100 affect a circuit containing an electro-responsive device, which may give an indication or alarm, or put into action a device which will 105 reduce the heat generation.

110 In place of the magnet and pivoted armature shown in Fig. 1, a solenoid and core may be used as indicated in Fig. 8. Here the solenoid coil 31 in circuit with the variable resistance 7 acts to control the position of its core 32, and consequently the opening or 115 closing of the switch for short circuiting the resistance 4. Various adjustments may be applied to the solenoid and switch such as change in turns or position of coil 31, position of contacts, weight and lower position of core, and resistance of the circuit containing coil 31 or of a shunt resistance about coil 31, etc., and these various adjustments may be applied to many of the constructions described 120 herein as will of course be understood.

In Fig. 9 is shown an arrangement in which a relay is used but which is somewhat different from the construction and connections of Fig. 3. In the present figure, the switch 33 is controlled by the coil 31 and opens or closes a shunt circuit about the coil 34. The latter is in circuit with the heating resistance 3. The coil 34 through its core, controls a switch 35 which includes or cuts out the resistance 4 from the circuit of the heating resistance 3. When the apparatus is connected to the supply wires a comparatively strong current will flow through the resistance 7 and coil 31 and raise core 32, thereby opening switch 33. This will cause the current through coil 34 to raise switch 35 and cut the resistance 4 out of the heating circuit. When the temperature of the heated parts rises to the maximum, the current in coil 31 will be so decreased as to cause the core 32 to fall and close switch 33. This action short circuits the coil 34, and the switch 35 will fall and cut resistance 4 in circuit. The heating effect is thus decreased until the temperature is such that the current in coil 31 causes its core to be raised, when the action above explained will again take place. The temperature is thus regulated within limits.

In Fig. 10, the raising of core 32 by the current in its coil opens switch 36 which shunts coil 34 connected across the line through a resistance 37. The heater 3 is connected across the line through a switch 38 controlled by the coil 34 and its core. Upon connecting to the supply line, the current in coil 31 will raise its core and open switch 36. This will cause current to flow through coil 34 and so close switch 38. Current then passes in resistance 3 and the temperature of the parts is rapidly increased. When switch 36 is afterward closed by reason of the higher temperature attained, the short circuiting of coil 34 will open switch 38 and the current to the resistance 3 will be interrupted. When the temperature sufficiently decreases, relay switch 36 will be opened and switch 38 closed as above explained.

In Fig. 11, instead of using separate heating and controlling resistances, a single resistance 39 is used of nickel, or iron, or other high temperature coefficient material. In circuit with the resistance 39 is the resistance 4, which is shunted when switch 40 is closed. This switch is controlled by coil 41 and its core and this coil is in circuit with the entire coil 42, which controls switch 43. When switch 43 is closed, it shunts a part of coil 42 and also shunts coil 41. When the device is connected to a source, current will first flow through coil 42, coil 41 and heater 39. This will be sufficient to raise the cores of coils 42 and 41, closing switch 43 and opening switch 40. The closing of switch 43 however, short circuits coil 41 so that switch 40 will be closed and a considerable current will pass through

a portion of coil 42, switch 43, switch 40 and heating resistance 39. Although some turns of coil 42 are cut out at this time, its core will still be raised on account of the increased current flow and on account of less excitation being required to hold the core after being raised. Adjustment of the number of turns cut out, will give a suitable relationship. As the temperature of the resistance 39 and other part or parts heated rises, the current through the remaining effective turns of coil 42 gradually becomes less owing to the increase of resistance of 39. The core of coil 42 will finally drop when the maximum temperature is reached and so open switch 43. This will cause the current to pass through the remaining turns of coil 42 and also through coil 41 which will raise its core and open switch 40. The complete path of the current will then be coil 42, coil 41, resistance 4 and resistance 39. The reduced strength of this current cuts down the heating effect of 39, but as the temperature decreases the resistance of 39 becomes less and the current strength gradually rises. When this is sufficient to raise the core of coil 42, the switch 43 will be closed and the increased current will flow through resistance 39 as above described. The temperature is thus closely regulated and without requiring the use of separate heating and controlling resistances.

In some cases, I may apply my invention to the control of an electric current or electromotive force; in such a case the heat responsive resistance will be arranged in a circuit, the current in which is normally constant within limits. Change in the current strength will then change the resistance and this change in resistance may then be used either directly or indirectly to automatically prevent too wide a change from normal conditions. For example, in Fig. 12 is indicated a generator armature 44 supplying current to the mains 2, 2'. The field 45 is controlled by a variable resistance 46; the path of the field circuit being from line 2, through the field circuit 45, resistance 46 and its adjustable arm 47, through the resistance 48 of nickel or other material of considerable temperature to line 2'. The resistance 48 is shunted by a magnetic winding 49. The latter acts to attract or release the armature switch 50 in opposition to spring 51. The movement of the armature 50 controls the current to the reversible pilot motor 52, which latter regulates the position of the arm 47.

In operation the electromotive force supplied to the mains will be maintained substantially constant as follows: Suppose the electromotive force rises somewhat above the normal value, then since the resistance 48 is in circuit across the line, the increased current therethrough will raise its temperature and consequently force relatively more cur-

rent through the magnet winding 49. The magnet will attract its armature and cause it to engage contact 53 which will close a circuit as follows through the pilot motor:—from 5 main 2, through a resistance and the armature of motor 52 to a field winding 54, contact 53, armature switch 50 and to line 2'. This will cause the pilot motor to rotate in such a direction as to insert more of resistance 46 in the 10 field circuit and so lower the electromotive force generated. On the other hand, if the electromotive force becomes too low, the current in 48 will be less and as its temperature and resistance lowers, it will tend to take 15 more current from the winding 49. The force of spring 51 will then be stronger than that of the magnet and will draw the armature 50 to contact 55. The circuit through the pilot motor will then be the same except 20 that its field will be reversed, the field 56 now being excited instead of field 54 and in a reverse sense. The pilot motor will therefore rotate to cut out part of resistance 46 and so cause the generator to supply an increased 25 electromotive force. A practically constant electromotive force can thus be maintained.

In Fig. 13 is shown an arrangement of apparatus for maintaining a constant current in a desired circuit. An instance of a storage battery 57 is shown supplied from the mains 2, 2' and source 1. With the arrangement shown, a practically constant rate of charging may be maintained without danger of 30 objectionable effects from too rapid charging. In series with the battery 57 to be charged, is an adjustable resistance 46 controlled by the arm 47. Also in series therewith is the controlling resistance 48 of high 35 temperature coefficient material. A magnetic winding 49 is shunted about the resistance 48, as in Fig. 12. The winding attracts or releases its armature switch 50 to engage either contact 53 or 55. If the charging current 40 becomes too large, the increase in resistance of 48 causes the winding 49 to attract its armature, and the pilot motor will rotate to insert more of resistance 46 in series with the battery to reduce the current. 45 When, however, the current is too small, the resistance of 48 will be so low that a reduced current will pass through the winding 49 and so release its armature 50, which will engage contact 55. The field 56 of the reversible 50 motor will then be excited and cause the same to rotate in the opposite direction and so cut out more of resistance 46 to increase the current flow. A constant charging current within limits is thus maintained.

55 When my invention is applied to a heating device, it is desirable that there should be the best possible flux of heat from the source of heat to the device heated, and also to the heat responsive device. Various

constructions may be employed to secure a 65 high degree of heat conductivity between the heat generating resistance and the heat responsive resistance, when that is employed. I sometimes wind the heat generating wire and the heat responsive wire on a common 70 support, and they may be wound together, one over the other, or they may be displaced longitudinally with reference to each other. Sometimes, I enamel both wires upon a common 75 metallic support, such as copper.

In Figs. 14 and 15, I have indicated a construction of a soldering iron, in which a tube 58 of metal, porcelain, or other material, is shown having enameled thereon the heat producing and heat responsive resistances 3, 7, 80 Over the outside of this resistance tube is placed a yieldable material 59 having high heat conductivity, such as copper foil, copper gauze or copper wire. The whole is seated in a hollow shell formed of two semi-cylindrical parts, 60, 61. These are adapted to be drawn firmly together by the screws or bolts 62 passing through lugs or flanges on the parts 60, 61. There is thus secured an excellent heat conductive relationship between all parts of the soldering iron, so that there will be a quick response of the electro-responsive device upon change in temperature. The enamel used to hold the resistances in place should have a high fusing 95 point, and preferably a glazed surface. Instead of splitting the soldering iron as indicated in Figs. 14 and 15, a hole could be bored or formed therein and the resistance device with its copper sheathing could be 100 made to form a tight fit in the hole. A threaded engagement of the resistance unit with the inside of the soldering iron might be desirable.

In Figs. 16 and 17, a soldering iron is indicated having four tubes arranged ninety degrees apart, three of which, such as the tubes 63, are resistance units for producing the heat required, and the fourth tube 46 is a unit embodying the responsive resistance 105 7. The units are shown as surrounded by a good heat conductive yieldable sheathing 59, and are held firmly against the core 65 of the iron by means of the semi-cylindrical clamps 66. A cylindrical cover 67 of some 110 material having low heat conductivity, or lined with such material may be provided outside of the resistances to protect them from mechanical injury and to confine the heat generated.

In Fig. 18, I have indicated a desirable arrangement of the resistances in a flat iron. The resistances 68 are heat producing resistances, and may be in the form of tubular resistance units adapted to be connected in 115 series or in parallel with each other. The resistance 69 is the heat responsive resistance which may also be in the form of an enameled

tubular resistance unit, and is centrally located with reference to the heating resistances 68.

Having thus described my invention, I declare that what I claim as new and desire to secure by Letters Patent, is,—

1. The combination of a heat producing solid resistive conductor, an electric conductor whose resistance is responsive to a change 10 in temperature, and means controlled by said response for regulating the heat produced by said heat producing device.

2. The combination of a heat producing solid resistive conductor, a conductor whose 15 resistance is dependent upon the temperature, and electro-responsive means dependent upon change in the resistance of said conductor for regulating the heat produced by said heat producing device.

20 3. The combination of a heat producing solid resistive conductor, means for increasing and decreasing the production of heat by said device, a resistive conductor whose resistance varies according to the temperature 25 of the device heated, and means electrically responsive to said change in resistance for controlling said first named means.

4. The combination of a circuit comprising a solid electric heating resistive element, 30 said circuit having means for increasing and decreasing the current therein, a second circuit functionally related thereto in which the resistance is automatically responsive to the condition of said first circuit, and a device 35 responsive to change in current in said second circuit for controlling said means.

5. The combination of a solid heat producing conductor, a second conductor whose resistance is affected by the heat developed 40 in said first conductor, and means responsive to change of resistance in said second conductor for varying the amount of current flowing in said first conductor.

6. The combination of a heat producing 45 device comprising a solid heat producing resistive element, electro-responsive means for controlling the heat produced by said device and a heat responsive variable resistance for controlling said means.

50 7. The combination of an electrically heated device whose temperature is to be controlled, a heat producing device, a controlling electric circuit the resistance of which is responsive to the temperature of 55 said first named device, and an electro-responsive device responsive to a change in said resistance.

8. The combination in an electric heater of a heating element, a heat responsive resistance, and electro-responsive means controlled by a change in said resistance for regulating the current in said heater whereby a desired condition within certain limits is automatically maintained.

65 9. The combination of a heat generative

solid electric resistance, a heat responsive electric resistance functionally related thereto, and means responsive to change in said second resistance for controlling the heat generated by said first resistance to maintain 70 a desired condition of temperature.

10. In an electro-heating apparatus, the combination of a resistance which varies in response to change in temperature, and magnetic means responsive to such a variation in resistance for affecting said temperature.

11. In an electro-heating apparatus the combination of a resistance having a high 80 temperature co-efficient, and electro-responsive means subject to change in resistance for automatically maintaining a desired condition within limits.

12. In an electro-heating apparatus the combination of a medium or body whose 85 temperature is to be controlled, and a controlling circuit therefor containing a source of electromotive force and a heat responsive resistance.

13. The combination of a mass from which 90 heat is emitted at varying rates, and resistance-responsive means comprising a movable element for automatically supplying to said mass heat energy according to the demand.

14. The combination of a mass from which 100 heat is emitted at varying rates, and resistance-responsive means comprising a movable element for automatically maintaining the temperature of said mass within desired limits.

15. The combination of an electrically heated device which emits heat at variable rates, and means for automatically supplying energy to the device at rates substantially 105 proportional to the rates of heat emission by said device, said means comprising a heat responsive resistance, and a functionally related electro-responsive device.

16. The method of controlling the temperature of a mass or medium which consists in transmitting heat from said mass or medium to a heat responsive electrical means, varying a controlling electric current, controlling thereby the movement of an electro- 115 responsive device and thus controlling the supply of heat to said mass or medium.

17. The combination of a mass to be heated, electrical means for heating said mass, and separable material of high heat 120 conductivity compressed between said mass and said means.

18. In an electro-heating apparatus the combination of a heating circuit, a controlling circuit therefor, and a resistance in the 125 controlling circuit automatically responsive to the heat in the heating circuit whereby the heat produced in the heating circuit is automatically controlled.

19. In an electro-heating apparatus the 130

combination of a device to be heated, means for electrically heating said device, and an exterior electro-responsive device for controlling the heat developed in said first-
5 named device and responsive to the heat developed electrically.

20. In an electro-heating apparatus the combination of an electric heat producing device and means for automatically controlling the heat produced comprising a controlling resistance responsive to the temperature of said device.

21. The combination of means comprising a solid conducting electric heating element
15 for heating a device, a heat responsive resistance, and an electro - magnetic device controlled by said resistance for controlling said means.

22. In an electro-heating apparatus the combination of a source of electric energy,
20 heat generating means connected to said

source, and controlling means comprising a heat responsive resistance.

23. The method of electrically heating which consists in generating heat by the 25
passage of a current through a resistance, varying a controlling resistance by heat conducted thereto, and controlling by the said variation of resistance the rate at which the heat energy is generated.

24. The method of controlling heat which consists in varying a heat responsive resistance by conducting heat thereto, and controlling the rate of production of the heat by said variation in resistance.

In testimony whereof I affix my signature, in presence of two witnesses.

H. WARD LEONARD.
